CHAIR

Moses W. Arnold, Darlington, S. C., assignor to
 Pee Dee Chair Co., Inc., Darlington, S. C., a
 corporation of South Carolina

Application May 1, 1935, Serial No. 19,287

5 Claims. (Cl. 155—178)

My invention relates to improvements in chairs.

An important object of the invention is to provide a chair seat which is extremely simple in construction and cheap to manufacture, and which may be quickly and easily secured in place upon the chair.

A further object of the invention is to provide positive means for preventing the rearward creeping of the chair seat.

10 A further object of the invention is to so construct the chair seat and arrange the same in place that there is no tendency for the elements of the chair seat to break.

15 A further object of the invention is to provide a chair seat which will possess a substantial degree of yielding action.

Other objects and advantages of the invention will be apparent during the course of the following description.

20 In the accompanying drawing, forming a part of this application, and in which like numerals are employed to designate like parts throughout the same,

Figure 1 is a perspective view of a chair embodying my invention,

Figure 2 is a central vertical longitudinal section through the same,

Figure 3 is a horizontal section taken on line 3—3 of Figure 2,

30 Figure 4 is a transverse vertical section taken on line 4—4 of Figure 3, and

Figure 5 is an exploded perspective view of the seat.

In the drawing, wherein for the purpose of illustration is shown a preferred embodiment of my invention, the numerals 10 and 11 designate the rear and front posts or uprights of the chair, which are rigidly connected by upper side rounds 12, a front round 13 and a rear round 14, and any suitable number of additional rounds 15, as shown. The uprights or posts 10 project above the upper rounds and are connected by slats 16 to form the back of the chair.

45 My improved seat embodies a forward attaching rail 17 and a rear attaching rail 18, which are rigid, and these rails are provided upon their inner longitudinal edges with grooves 19 and 20, respectively, which are of substantial depth. These grooves receive the ends of slats 21 formed 50 of wood or the like, and these slats are sufficiently stiff to support the weight of the user of the chair, but possess substantial resiliency. These slats are preferably longitudinally curved in a horizontal plane. The ends of these slats project into the grooves 19 and 20, as stated, and these ends

are securely retained within the grooves and attached to the rails 17 and 18 by nails 22, which are driven upwardly through the bottom faces of the rails, and the ends of the nails terminate below the upper surface of the rails. It has been found that the nails alone are sufficient to retain the slats properly attached to the rails, but if desired, the ends of the slats may also be glued to the rails, within the grooves. The slats 21 may be arranged in parallel relation or they may 10 converge rearwardly, to correspond with the shape of the chair, as shown.

The seat has its forward and rear rails 17 and 18 arranged above and in contact with the rounds 13 and 14, while the outer side slats 21 are preferably arranged parallel with the side rounds 12, whereby the side rounds form, in effect, a continuation of the seat. The slats 21 are longitudinally bowed with their upper surfaces depressed, as shown. The forward rail 17 has its opposite 20 ends cut upon a transverse curve to provide curved shoulders or lips 23, which engages with the upper ends of the forward uprights or posts 11 in advance of the same, sufficiently to produce wedging action, if the seat should move rearwardly 25 with respect to the forward uprights. This is an important feature of the invention, as there is a tendency for the seat to shift rearwardly with respect to the body of a chair, during the use of the chair. The forward rail 17 is attached to 30 the upper round 13 by means of nails 24 or the like, which are preferably driven downwardly through the upper surface of the rail into the upper forward round 13, and preferably pass through the central longitudinal axis of the 35 round. Particular attention is called to the fact that the slats project into the groove 19 sufficiently so that they extend over the point of contact between the rail and round 13, so that the lower thin portion 17' of the rail, produced by the 40 groove, is properly supported, and there is no liability of the same breaking off, when the chair is subjected to an excessive strain. The rear rail 18 is attached to the round 14 by similar nails 25 or the like, driven in position in a similar manner, and the arrangement of the ends of the slats is such that the thin portion 18' of the rail 18 is 45 properly supported by the round against breaking action. The nails 24 and 25 have been found ample for holding the seat in position, operating 50 in conjunction with the engaging lips or flanges 23, and these nails produce a somewhat yielding connection between the rails 17 and 18 and the rounds 13 and 14, respectively, whereby a slight rolling action of the rails upon their longi-

tudinal axes, upon the rounds, may occur when weight is applied to the seat.

While I have shown my invention as embodied in a straight chair, it is in no sense restricted to this embodiment, as it may be embodied in a rocking chair.

In view of the foregoing description, it is believed that the mode of assembling the chair is obvious and that the chair is used in the ordinary manner. As stated, the slats 21 are sufficiently stiff to properly support the user of the chair, but are substantially resilient so that a slight yielding action will occur, when weight is applied to the seat. Since the rails 17 and 18 are also yieldingly secured to the rounds, these rails may partake of a limited rocking action upon the rounds, when the slats 21 flex or yield, in a limited manner, as stated.

It is to be understood that the form of my invention herewith shown and described is to be taken as a preferred example of the same, and that various changes in the shape, size and arrangement of parts may be resorted to without departing from the spirit of my invention or the scope of the subjoined claims.

Having thus described my invention, I claim:

1. A chair comprising front and rear uprights, upper front and rear side rounds connecting the uprights, a seat comprising forward and rear rails provided upon their inner edges with grooves, slats having their ends held within said grooves, the rails being mounted upon the forward and rear rounds in such a manner that the ends of the slats extend over the points of contact between the rails and rounds, and means to yieldingly attach the rails to the rounds to permit of limited rolling movement thereon.

2. A chair comprising forward uprights and rear uprights, means connecting the uprights including upper side rounds and forward and rear rounds, a seat comprising forward and rear rails provided upon their inner edges with longitudinal grooves, resilient slats having their ends held within the grooves, the rails being mounted upon the forward and rear rounds in such a manner that the ends of the slats project over the points of contact between the rails and rounds, and yielding means attaching the rails with the forward and rear rounds to permit of a limited rocking movement of the rails upon the rounds.

3. A chair comprising forward uprights and rear uprights, means connecting the uprights including upper side rounds and forward and rear rounds, a seat comprising forward and rear rails provided upon their inner edges with longitudinal grooves, resilient slats having their ends held within the grooves, the rails being mounted upon the forward and rear rounds in such a manner that the ends of the slats project over the points of contact between the rails and rounds, yielding means attaching the rails with the forward and rear rounds to permit of a limited rocking movement of the rails upon the rounds, and means to limit the rearward movement of the seat with relation to the uprights.

4. A chair comprising forward and rear uprights, means connecting the uprights comprising side rounds and upper forward and rear rounds, a seat comprising forward and rear rails provided with grooves upon their inner edges, slats having their ends held within the grooves, the slats constituting the sole connecting means between the rails, the rails being mounted upon the forward and rear rounds in such a manner that the ends of the slats project over the points of contact between the rails and rounds, and elements attaching the rails to the forward and rear rounds, the side slats being generally parallel with the side rounds.

5. A chair comprising forward and rear uprights and means connecting the uprights including upper forward and rear rounds, a seat comprising forward and rear rails provided upon their inner edges with grooves, slats having their ends inserted within the grooves, nails driven upwardly through the lower faces of the rails and securing the slats within the grooves, the slats constituting the sole means connecting the rails, the rails being arranged upon the forward and rear rounds so that the ends of the slats will project over the points of contact between the rails and rounds, nails attaching the rails to the forward and rear rounds and driven through the upper surface of the rails, and extensions formed upon the ends of the forward rail for engaging the forward uprights to limit the rearward movement of the forward rail.

MOSES W. ARNOLD.
